UNITED STATES PATENT OFFICE

DANIEL H. CHASON, OF ELIZABETH, NEW JERSEY, ASSIGNOR TO THE SINGER MANUFACTURING COMPANY, OF ELIZABETH, NEW JERSEY, A CORPORATION OF NEW JERSEY

WORKHOLDER FOR SEWING MACHINES

Application filed July 30, 1930. Serial No. 471,676.

This invention relates to devices for holding stretched for the stitching operation a section of work to be darned or embroidered, while holding the surrounding portions of the work securely out of the path of the sewing machine needle.

The invention aims to provide a work-holder of this character with improved means for securely holding the portions of the work surrounding the stretched portion.

The invention consists in the devices, combinations and arrangements of parts herein-after described and claimed.

The features of the invention and the advantages attained thereby will be obvious to those skilled in the art from the following detailed description of a preferred embodiment of the invention, taken in connection with the accompanying drawings, in which Fig. 1 is a perspective view of a work-holder embodying the invention. Fig. 2 is a transverse section through the work-holder adjacent one of the movable work-holding fingers. Fig. 3 is a section through one of the bearings for a work-holding finger and Fig. 4 is a perspective view of a work-holding finger in unprung or unstrained condition, before it is engaged with its supporting bearing.

The invention is disclosed as embodied in a work-holder constructed substantially in accordance with the disclosure of the U. S. patent to De Voe, No. 939,894, issued Nov. 9, 1909.

The stretching frame comprises an endless band or hoop 1 of sheet metal having an external channel 2 formed by the lower continuous lip 3 and the series of upper spaced lips 4 intermediate which rise the arms 5 having at their upper ends the bearing loops 6 which embrace the relatively resilient inwardly directed bearing ends 7, 7 of the work-holding fingers 8, each of which comprises a piece of stout springy wire doubled upon itself at 9 and bent to hook form, Fig. 2.

The ends 7 of each finger 8, which are relatively resilient, are preferably formed initially out of alinement, as shown in Fig. 4, so that when embraced by a bearing loop 6 they will be held under strain and will fric-

tionally resist turning of the finger 8 in its bearing. Considerable wear in the bearings will not impair the frictional operation of the fingers, as the long connecting lengths of spring wire between the ends 7 of each finger give a considerable range of spring action between such ends 7 to take up any wear in the bearings.

Intermediate the relatively spaced lips 3, 4 and lying within the channel 2 is arranged the usual detachable elastic band 10, such as disclosed in the De Voe Patent No. 939,894, previously referred to.

Having thus set forth the nature of the invention, what I claim herein is:

1. A work-holder comprising a ring-shaped frame-element over which the work is stretched, an elastic band cooperating therewith in clamping the margin of that portion of the work stretched across said frame-element, and a series of independently movable spaced work-embracing finger-elements each having a bearing engagement with said frame-element, said finger-elements being each initially formed with bearing end-portions out of alinement, said end-portions being held sprung into alinement by their bearing engagement with said frame-element.

2. A work-holder comprising a ring-shaped sheet metal frame formed at intervals with upstanding tongues terminating in bearing loops, and a series of work-holding fingers journaled in said bearing loops for swinging movement, each of said fingers comprising a wire doubled upon itself midway of its ends and bent to hook form, the ends of each wire being bent to extend toward each other and being embraced by the bearing loop of its respective supporting tongue, each wire being initially formed with its ends out of alinement, said ends being held sprung into alinement by its respective supporting bearing loop.

In testimony whereof I have signed my name to this specification.

DANIEL H. CHASON.
